W. E. KISTLER

AUTOMOBILE BUMPER

Filed Nov. 26, 1923

Inventor:

Walter E. Kistler.

Patented June 24, 1924.

Des. 64,979

UNITED STATES PATENT OFFICE.

WALTER E. KISTLER, OF FORT WORTH, TEXAS.

DESIGN FOR AN AUTOMOBILE BUMPER.

Application filed November 26, 1923. Serial No. 7,893. Term of patent 14 years.

To all whom it may concern:

Be it known that I, WALTER E. KISTLER, a citizen of the United States, residing at Fort Worth, in the county of Tarrant and State of Texas, have invented a new, original, and ornamental Design of an Automobile Bumper, of which the following is a specification, reference being had to the accompanying drawing, forming part thereof.

The figure is a perspective view of an automobile bumper showing my new design.

I claim:

The ornamental design for an automobile bumper as shown.

WALTER E. KISTLER.
